UNITED STATES PATENT OFFICE.

JOHN J. MORSE, OF CLEVELAND, OHIO, ASSIGNOR TO BURROUGHS ADDING MACHINE COMPANY, OF DETROIT, MICHIGAN, A CORPORATION OF MICHIGAN.

KEY-DRIVEN CALCULATING MACHINE.

Application filed October 5, 1923. Serial No. 666,683.

To all whom it may concern:

Be it known that I, JOHN J. MORSE, a citizen of the United States, residing at Cleveland, in the county of Cuyahoga and State of Ohio, have invented certain new and useful Improvements in Key-Driven Calculating Machines, of which the following is a specification.

The invention relates to safeguards for key-driven calculators whereby incomplete key-action is prevented and consequent error in calculation eliminated. The particular object in view may be said to be the provision of simple, easily applied and reliable means for such purpose adapted to the Burroughs type of calculator. As to the latter reference may be had to Gooch Patent No. 1,128,679 issued February 16, 1915, Gooch Patent No. 1,150,937, issued August 24, 1915, Horton Patent No. 1,156,600, issued October 12, 1915 and Horton Patent No. 1,326,504, issued December 30, 1919. Without multiplication of parts or any complication of mechanism but by the introduction of a very few simple parts in each numerical order I provide for locking the registering transmission mechanism so that no additive movement thereof can take place until a key has been fully depressed. A partially depressed key becomes locked against restoration. Through the same devices I provide for locking said mechanism so as to prevent re-depression of a key that has been fully depressed but has not been completely restored. Thus I effectively provide against such manipulation as the so-called "pumping" of a key which is sometimes practiced with the object of demonstrating defective performance of a key-driven calculator.

In the drawings which accompany and form part of this specification Fig. 1 represents an elevation of on ordinal section of one of these machines with my invention incorporated therein and all parts shown at normal; some being broken away to economize space or better disclose parts beyond; Fig. 2 is a detail elevation on a larger scale showing the normal state of certain parts by which the invention is embodied; Fig. 3 is a similar view showing the abnormal state of the same parts; Fig. 4 is a cross-section taken substantially on the line 4—4 of Fig. 1; Fig. 5 is a detail perspective of one of the parts of my invention; Fig. 6 is a sectional plan view taken substantially on the

line 6—6 of Fig. 7; and Fig. 7 is an elevation similar to Fig. 1 of the front portion of the machine under a condition corresponding with that illustrated in Fig. 3.

I shall first refer to some of the familiar mechanical elements of the machine with which those parts supplied by my invention are more intimately related. The stems of the numeral keys are designated 2 and they operate upon a horizontal lever 3 that is pivoted at its rear end to the forward corner of a triangular lever 4 and is connected at its forward end by a link 5 with a bar 6. The latter is pivotally connected at its rear end to the upper corner of the triangular lever 4 and at its forward end to a gear segment 7. It has stop shoulders 6^a to strike against the key stems and so limit the movement of the actuator elements in accordance with the key-values. Depression of a key drives downwardly the lever 3, rocking the triangular lever 4 forwardly and thrusting the bar 6 forwardly and so swinging the gear segment 7 in a counterclockwise direction. The latter is in mesh with a pinion 8 carrying a driving pawl 9 (Fig. 2) which engages an internal ratchet 10^a of a gear wheel 10. During key-depression the pawl trips clockwise over the teeth of the ratchet and on release of the key a spring 11 pulls up the lever 4 and through the described connections causes the pawl to drive the ratchet in a counterclockwise direction. The motion is transmitted to the numeral wheels 12 in a familiar manner and as set forth in the said Gooch Patent No. 1,128,679. Driving connections of the character above described may be seen in the Horton Patent No. 1,156,600.

In order to prevent the driving and driven members from getting out of step or the driven member from over-running, a notched disc 13 is secured to the driving pinion 8, and the ratchet gear wheel 10 meshes with a pinion 14 which carries a mutilated pinion or toothed disc 15. This expedient is the subject of the said Gooch Patent No. 1,150,937 and as there explained the notched disc and mutilated pinion are so related that in clockwise rotation of the former (caused by depression of a key) it moves independently of the mutilated pinion, passing freely through the space between two of the latter's teeth. When the

95

100

105

110

notched disc rotates counterclockwise (during the rise of the depressed key) the toothed disc or mutilated pinion is rotated clockwise (through the intermeshing of the driven gear wheel 10 and the pinion 14), the teeth of the mutilated pinion successively inter-engaging with the notches of the disc 13.

I apply my novel key control to the just-described preventive means which readily lend themselves to the accomplishment of my purpose. Thus I mount upon a frame cross-rod 16 (located just above the pinions 14, 15) a double-acting pawl and detent piece which appears in all of the figures of the drawings and is separately shown in perspective in Fig. 5. It will be seen to comprise a pendent branch 17 with a forwardly turned lower end to coact with the toothed disc 15, and an upper forwardly extending branch 18 with a down-turned nose overhanging the notched disc 13. In order to best provide for pivotal mounting of this piece it is made in yoke form horizontally, as best seen in Fig. 5, the sides of the yoke being perforated to afford spaced pivotal bearings for the piece upon the frame cross-rod 16. The cross bar 19 of the yoke has an up-standing ear to which one end of a spring 20 is attached, the other end of said spring being attached to a frame stud 21. It will be seen that this spring tends to throw the nose of the pawl 18 against the periphery of the notched disc 13. The spring is normally restrained from so acting by reason of the engagement of a stud 22 with the back of the pendent detent 17, as shown in Figs. 1 and 2, which also results in the holding of the bent end of the latter in the path of one of the teeth of the mutilated pinion 15. This condition obtains throughout the downstroke of any one of the numeral keys, from which it follows that clockwise turning of the latter will be prevented and no driving of the ratchet gear wheel 10 by the pawl 9 can occur. Hence release of a partially depressed key cannot result in transmission of movement to the registering wheel.

The aforesaid stud 22 is carried by the upper arm 23 of a lever which lies against a division plate 24 of the framework and is pivoted thereto at the middle, as shown at 25. The lower arm 26 of this vertically disposed lever is recessed in its forward edge and there engaged by the pivot stud 27 that connects the driving segment 7 and the horizontal bar 6, said stud projecting through an arcuate guiding slot 28 in said division plate.

In the normal rearward position of the said stud 27 it holds the lever 23-26 with its stud 22 against the back of the pendent detent 17 so that the latter is maintained in its effective position blocking the transmission mechanism in the manner already ex-

plained. The lower end of the said vertically disposed lever takes the form of a substantially square lug which normally occupies the complementally formed notch of a long latch lever 30. The latter is pivoted at its rear end to the said division plate as shown at 29 and extends forwardly along the same and adjacent the entire series of keys. It has a depending goose-neck formation 30^a at the front end where the aforesaid notch is provided. The latch lever is upheld by a spring 31 connecting it with the division plate and it is held against the latter by a headed stud 32 which is embraced by a notch formed in the latch lever as shown in Figs. 1 and 7. The latch lever has a series of stepped and graduated shoulders 33 designed to be struck respectively by the lateral lugs 37 of the key stems, which lugs occupy guiding slots in the division plate, as usual. When any depressed key reaches the end of its downstroke its lateral lug will strike and depress the latch lever thereby releasing the vertically disposed lever. Meanwhile the segment stud 27 will have advanced in the guide slot 28 so that the spring 20 will rock the pawl and detent piece and disengage its detent piece 17 from the toothed disc 15, the lever 23-26 turning clockwise on its pivot. Thus the transmission mechanism will be unlocked so that upon the rise of the fully depressed key the registering function of the machine will be performed in the usual manner.

Passing to the matter of a safeguard against re-depression of a key that has been fully depressed but not permitted to fully restore, the above described rocking of the pawl and detent piece by its spring throws the nose of its upper member 18 against the periphery of the notched disc 13 so that when the latter turns counterclockwise its notches will successively slip past the pawl-nose but any reverse (clockwise) turning of said disc while the detent piece is so conditioned will result in the pawl-nose jamming between the upper side of a notch of the disc and the point of a tooth of the mutilated pinion 15, as illustrated in Fig. 3. This is what will happen if a key that has been fully depressed is not permitted to completely restore and an attempt is made to again depress it, for the detent piece remains conditioned as above explained until the driving segment 7 completes its return stroke as permitted by the full rise of the depressed key. The result is that the key is locked against re-depression until permitted to complete its upstroke. As the segment 7 completes its return stroke its stud 27 rocks the lever 23-26 and the detent piece is forced to its normal position. The latch lever 30, having been depressed at the very end of the down-stroke of the key will correspondingly be released at the

beginning of the upstroke of the key but, with the vertically disposed lever in its abnormal position, the terminal edge of the goose-neck will strike against the bottom 5 edge of the vertically disposed lever, and then when the latter is rocked to its normal position the latch lever will be further lifted by its spring so that its notch re-engages with the said lever.

10 In order that a partially depressed key may be prevented from rising and may thus indicate to the user that an incomplete operation has been performed, I provide for coupling each key to the actuating lever 3.

15 To this end the feet 2^a of the key stems which closely overlie the upper edge of the actuating lever 3 and impart motion to said lever, are made with holes 2^b, and the lever is made with forwardly-turned hooks 3^a to 20 enter said holes, respectively. These hooks stand closely adjacent the rear sides of the respective key-stems as shown in Fig. 1, so that as soon as depression of any key starts and its foot acts upon the lever 3, with the 25 result of swinging the latter forward as well as downward, the hook will enter the hole and the key stem will be coupled to the lever as illustrated in Fig. 7. Consequently the key cannot rise independently 30 of the lever and since the lever will be blocked against rising so long as the detent piece obstructs the mutilated pinion, it follows that if the key is only partly depressed and then released, it will remain in depressed position. Of course if the key is 35 fully depressed it will rise with the lever and as the upstroke is completed will become disengaged from the coupling hook, and the key will be lifted slightly off the 40 lever by its own spring 34.

On zeroizing when the numeral wheels turn backward, as explained in said Horton Patent No. 1,326,504, the ratchet gear wheels 10 must be free to turn counter-clockwise and the pinions 14 and 15 correspondingly clockwise, and so the special 45 detents for compelling full key-strokes should not be in their normal obstructing relationship to said pinions. All that is 50 required in this regard is to so proportion and so laterally relate the bent ends of the detents 17 to the teeth of the mutilated pinions 15 as to provide for removal of the latter from the planes of the detents when 55 the pinions are shifted laterally in a zeroizing operation. As fully shown and described in said Horton patent, the pinions are 60 slideable upon a transverse shaft which is itself laterally shiftable and is so shifted in a zeroizing operation as to take the mutilated pinions out of line with the notched discs. Coiled springs surrounding the shaft hold the pinions in proper position thereon. In the accompanying drawings the corre- 65 sponding shaft is designated 35 and the par-

ticular one of the coiled springs appearing in Fig. 6 is designated 36. The bent ends of the detents 17 are made sufficiently narrow and so related to the mutilated pinions that the lateral shift of the latter in a zeroizing operation takes them out of line with the detent. 70

It will be seen that the construction above described accomplishes the object primarily stated herein. At the same time it is to be understood that my invention is not necessarily limited to the precise form of embodiment here shown, nor to use only as adapted to the selected make of calculator. 75

I claim:

1. In a machine of the class described, the combination with registering mechanism, depressible keys, actuators, transmission mechanism including driving and driven members, and means for keeping said members in step; of devices applied to said means normally blocking additive movement of the driven member, with provisions for unblocking at the end of the downstroke of a key and for interposing an obstruction against redepression of such key prior to completion of its upstroke. 80

2. In a machine of the class described, the combination with registering mechanism, depressible keys, actuators, transmission mechanism including driving and driven members, and means for keeping said members in step; of devices applied to said means normally blocking additive movement of the driven member, with provisions for unblocking at the end of the downstroke of a key and for interposing an obstruction against redepression of such key prior to completion of its upstroke; and also provisions for coupling the key to the actuator 100 from the time the key starts down to the time it completes its return stroke. 105

3. In a machine of the class described, the combination with registering mechanism, depressible keys, actuators, and transmission mechanism including driving and driven members; of a single detent piece adapted under a normal setting to block the driven member and under a different setting to block the driving member, and means for changing the setting of the detent piece upon completion of the down-stroke of a key, with provisions for resetting the piece upon completion of the upstroke of the key. 110 115

4. In a machine of the class described, the combination with registering mechanism, depressible keys, actuators, and transmission mechanism including driving and driven members; of a single detent piece adapted under a normal setting to block the driven member and under a different setting to block the driving member, a spring for shifting the detent piece, and a latch normally restraining the spring and adapted to be displaced by a key as the 120 125 130

4
same completes its downstroke, together with provisions for maintaining the unlatched condition during the upstroke of the key and for resetting the detent piece by the actuator at the conclusion of the latter's return movement.

5. In a machine of the class described, the combination with registering mechanism, 10 depressible keys, actuators, and transmission mechanism including driving and driven members; of a single rocking detent piece adapted under a normal setting to block the driven member and under a different setting to block the driving member, 15 a spring for shifting the detent piece, a lever engaging the latter and normally held by the actuator, and a latch engaging the lever and adapted to be displaced by a key as the same completes its downstroke, with 20 provisions for maintaining the unlatched condition until the key completes its upstroke.

6. In a machine of the class described, the combination with registering mechanism, 25 depressible keys, actuators, transmission mechanism including driving and driven members, a notched disc on the driving member, and a toothed disc geared to the driven member; of a rocking detent and 30 pawl piece one branch of which normally intercepts a tooth of the toothed disc and the other branch of which is adapted to engage the notched disc, a spring applied to the said piece for effecting the latter engagement, and means controlled by the keys 35 and the actuator for normally restraining the spring whereby after movement of the actuator by key depression and upon completion of the downstroke of the key the 40 detent and pawl piece will be released and disengaged from the toothed disc and engaged with the notched disc.

7. In a machine of the class described, the combination with registering mechanism, 45 depressible keys, actuators, transmission mechanism including driving and driven members, a notched disc on the driving member, and a toothed disc geared to the driven member; of a rocking detent and 50 pawl piece one branch of which normally intercepts a tooth of the toothed disc and the other branch of which is adapted to engage the notched disc, a spring applied

to the said piece for effecting the latter engagement, a lever engaged on one side of 55 its pivot with the said piece and on the other side of its pivot by the actuator, and a latch engaging said lever and operated upon by a key as the same completes its downstroke.

60 8. In a machine of the class described, the combination with registering mechanism, depressible keys, an actuator lever and segment, transmission mechanism including driving and driven members, a notched disc 65 on the driving member, and a toothed disc geared to the driven member; of a rocking detent and pawl piece one branch of which normally intercepts a tooth of the toothed disc and the other branch of which is adapted 70 to engage the notched disc, a spring applied to the said piece for effecting the latter engagement, a lever engaged on one side of its pivot with said piece and on the other side of its pivot by the actuator segment, 75 and a latch engaging said lever and operated upon by a key as the same completes its downstroke.

80 9. In a machine of the class described, the combination of an actuator lever having hook formations, depressible keys with holes confronting the latter and adapted to be entered thereby upon movement of the actuator lever by the keys, registering mechanism, transmission mechanism including 85 driving and driven members, detent means associated therewith and normally obstructing the driven member, and means for removing the obstruction upon completion of the downstroke of a key.

90 10. In a machine of the class described, the combination of an actuator lever having hook formations, depressible keys with holes confronting the latter and adapted to be entered thereby upon movement of the 95 actuator lever by the keys, registering mechanism, transmission mechanism including driving and driven members, a toothed disc geared to the driven member, a rocking detent normally intercepting a tooth of said disc, a lever normally held by the actuator and holding the detent in such intercepting position, and a latch engaging said lever and operated upon by a key as the same completes its downstroke.

JOHN J. MORSE.
